UNITED STATES PATENT OFFICE

169,478

PLATE OR SIMILAR ARTICLE

David Goldrosen, Worcester, Mass., assignor to
Dapol Plastics, Inc., Worcester, Mass., a corpora-
tion of Massachusetts

Application June 26, 1952, Serial No. 20,360

Term of patent 3½ years

(Cl. D44—15)

To all whom it may concern:

Be it known that I, David Goldrosen, a citizen of the United States, residing at Worcester, in the county of Worcester, and State of Massachusetts, have invented a new, original, and ornamental Design for a Plate or Similar Article, of which the following is a specification, reference being had to the accompanying drawing forming part thereof.

The figure of the drawing shows a plan view of a plate or similar article of conventional configuration embodying my new design.

The dominant feature of my design resides in the surface ornamentation of the plate or similar article.

I claim:

The ornamental design for a plate or similar article, substantially as shown and described.

DAVID GOLDROSEN.
